UNITED STATES PATENT OFFICE.

HORACE B. HEMINGWAY, OF NEW HAVEN, CONNECTICUT, ASSIGNOR TO WINCHESTER
REPEATING ARMS CO., OF NEW HAVEN, CONNECTICUT, A CORPORATION.

TWO-PART SELF-LOCKING RIVET FOR TOOL-HANDLES.

1,339,198.

Specification of Letters Patent.

Patented May 4, 1920.

Application filed November 1, 1919. Serial No. 335,138.

To all whom it may concern:

Be it known that I, HORACE B. HEMINGWAY, a citizen of the United States, residing at New Haven, in the county of New Haven and State of Connecticut, have invented a new and useful Improvement in Two-Part Self-Locking Rivets for Tool-Handles; and I do hereby declare the following, when taken in connection with the accompanying drawings and the characters of reference marked thereon, to be a full, clear, and exact description of the same, and which said drawings constitute part of this application, and represent, in—

Figure 1. An enlarged view in transverse section of a tool-handle showing the use of my improved rivet.

Fig. 2. A view in elevation showing the two identically alike complementary parts of my improved rivet as positioned preparatory to being clenched.

Fig. 3. A detached view in elevation of one of the said parts.

Fig. 4. A corresponding edge view thereof.

My invention relates to an improved two-part self-locking rivet particularly designed for securing the handle-scales of knives to the handle-tangs thereof but also applicable for use in the manufacture of screw-drivers, wrenches and a wide range of kindred tools having handle-scales, the object being to provide simple and efficient means for securing the scales in place.

With these ends in view my invention consists in a two-part, self-locking rivet composed of two identically alike complementary parts having certain details of construction as will be hereinafter described and pointed out in the claims.

In carrying out my invention as herein shown, I produce a rivet of two identically alike complementary parts each of which consists of an overhanging head 2, and a relatively long, slender shank comprising a cylindrical butt 3 and a semi-circular spur 4 the face of which lies in the median longitudinal plane of the butt. The face of the spur 4 merges at its butt end into a curved shoulder forming a deflecting-surface 5, while at its outer end the face of the spur is

formed with a corresponding reversely curved deflecting-surface 6. These two parts, when fitted together as shown in Fig. 2, unite to form a double headed rivet joined by what is tantamount to a cylindrical shank.

In using my improved rivet as shown in Fig. 1, its respective parts are passed in opposite directions through suitable alined countersunk transverse holes 7 formed in handle-scales 8 applied to a handle-tang 9 having a circular hole 10 alined with the holes 7 aforesaid and adapted in diameter to receive with a snug fit the shank formed by the juxtaposition of the spurs of the respective parts of the rivet as shown in Fig. 2. The parts with their spurs thus held together by the walls of the hole 10, are now driven together whereby the spurs are caused to ride one upon the other, the deflecting-surface at the outer end of one spur engaging with the deflecting-surface at the base of the other spur and vice versa, and whereby the outer ends of the spurs are curled outward and caused to penetrate into the wood of the handle-scales which are thus clenched upon the handle-tang which meanwhile and always holds the two spurs together at a point about midway of their length as shown in Fig. 1. The handle-scales, the handle-tang and the two parts of the rivet are thus firmly locked together.

I claim:

A two-part self-locking rivet consisting of two identically alike complementary parts, each having an overhanging head and a shank comprising a cylindrical butt and a semi-circular spur the face of which lies in the median longitudinal plane of the butt, there being a curved deflecting-surface between the face of the spur and its butt and the outer end of the spur being reversely curved to form a deflecting-surface.

In testimony whereof, I have signed this specification in the presence of two subscribing witnesses.

HORACE B. HEMINGWAY.

Witnesses:

DANIEL H. VEADER,
ERIK S. PALMER.
